IRVING COOPERSTEIN AND ABRAHAM COOPERSTEIN, OF BROOKLYN, AND ABE LEVITT,
OF NEW YORK, N. Y.

DESIGN FOR A CANDELABRUM

Application filed November 17, 1932. Serial No. 46,017. Term of patent 3½ years.

To all whom it may concern:

Be it known that we, IRVING COOPERSTEIN, ABRAHAM COOPERSTEIN, and ABE LEVITT, citizens of the United States, residing at 157 E. 38th St., Brooklyn, New York, 3452 Bedford Avenue, Brooklyn, New York, and 40 W. 17th St., New York, New York, respectively, have invented a new, original, and ornamental Design for a Candelabrum, of which the following is a specification, reference being had to the accompanying drawing, forming part thereof.

We claim:

The ornamental design for a candelabrum, as shown.

In witness whereof, we hereunto subscribe our names this 15th day of November, 1932.

IRVING COOPERSTEIN.

ABRAHAM COOPERSTEIN.
